ANIMATED PICTURE LAMP

Robert Y. Allen, Encino, Calif., assignor of one-half to Leonard M. Poole, Los Angeles, Calif.

Application February 6, 1946; Serial No. 645,819

5 Claims. (Cl. 88—16)

1

The present invention relates generally to lamps and lighting fixtures, and more particularly to such fixtures as are used for display, amusement, and advertising purposes. While the embodiments of the invention shown herein are table lamps adapted to be used in nurseries and like places for the amusement of children, this use is to be regarded as typical only, and I do not mean to be limited to this field of use.

The attractiveness of animated cartoons particularly to children has long been known, and the animation device known as the zoetrope has sometimes been used to provide short animated cartoon sequences in a simple form such as is adapted for use by children.

The construction of the conventional zoetrope is very well known. It consists of a flat circular band or hoop with a series of evenly spaced transverse slots formed therein and with the sequence of animated cartoon pictures imprinted on the interior surface of the band, one picture falling between each pair of successive slots. When such a device is rotated about its axis and the cartoon pictures observed through the slits, the illusion of motion is produced due to the stroboscopic scanning action of the moving slits.

The zoetrope, as used in the past however, has several disadvantages. For one thing, it has been the usual practice to rotate the device manually and due to the uneven speed of rotation achieved in this manner, it was usually impossible or extremely difficult to achieve the appearance of natural motion in the cartoon.

Another disadvantage of the zoetrope used as just described lies in the fact that the intensity of illumination falling on the cartoon pictures is at best only equal to the intensity of illumination of the outer surface of the band. As a result of this type of illumination, the counter-directional motion of the slits past the eye tends to blur or "fog" the image of the picture, and to avoid the effects of this blurring, on the one hand it is necessary to place the eye relatively close to the scanning slits. With the eye placed close to the slits in this manner, however, the resolving power of the slit becomes relatively low and the definition of the image is much less sharp than if viewed from a relatively distant point. For this reason it is desirable that the interior surface be relatively brightly lighted as compared to the outside surface. This being done, the picture can be viewed from a relatively distant point and the outer surface of the band being relatively unilluminated, will not produce the aforesaid "fogging."

2

It is a major object of my invention to provide a lamp and shade structure suitable for use as an amusement or display device which embodies an animated cartoon viewable from outside the shade.

It is another object of my invention to provide a lamp embodying an improved zoetrope which is rotated at a constant speed thus to give the illusion of natural motion.

10 It is a further object of my invention to provide a zoetrope which is illuminated from inside the band thus to eliminate the fogging of the picture image as above described.

15 A still further object of my invention is to provide a zoetrope in which the animated picture may be viewed from various positions outside the shade.

These and other objects of my invention will become apparent from a consideration of the 20 following description taken in connection with the accompanying drawings.

Briefly described, one lamp constructed according to my invention makes use of a more or less conventional drum shaped shade mounted 25 to the shaft of a small electric motor for rotation about a vertical axis. Near the lower edge of the shade is formed a series of evenly spaced relatively narrow slits parallel to the axis of the shade. A series of cartoon pictures is imprinted 30 on the interior surface of the shade, each picture in the series falling between a pair of successive slits. The lamp is provided with the usual type of light globe mounted within the shade. Thus it will be seen that the aforementioned disadvantages are largely overcome since the shade is rotated at a relatively uniform motion by the electric motor, and since the source of illumination for the pictures lies within the shade.

35 40 For a more detailed description of my invention reference should now be had to the attached drawings in which:

Fig. 1 is a perspective view of a child's table lamp constructed according to my invention,

45 Fig. 2 is a top plan view of the device shown in Fig. 1 but with the base portion omitted.

Fig. 3 is an elevational section view of the lamp portion shown in Fig. 2 taken on the line 3—3 in Fig. 2, and

50 Fig. 4 is a fragmentary elevational view of the motor employed in the device shown in Fig. 1.

Referring now to the drawings, the lamp illustrated generally in Fig. 1 comprises a flat circular base 10 having an upstanding columnar support 11 fixed thereto and additionally sup-

ported by a reclining ornamental figure 12. Fixed to the top of columnar support 11 and projecting leftwardly therefrom is a flat plate 13. Mounted on the left end of the plate 13 and positioned with its rotational axis in a vertical position, is a small motor 14 of the type generally used to motivate electric clocks. The armature portion of the motor 14 consists of an aluminum cup 15 with a suitable band of magnetic material (not shown) affixed thereto. A shaft 16 is affixed to the armature 15 and journally mounted for rotation therewith, projecting upwardly as best seen in Fig. 4. A drum shaped shade 19 for the lamp constructed from opaque material is supported by a hollow central hub 17 to which are fixed three outwardly projecting spokes 18 attached to the shade 19 at its upper rim.

As can be best seen in Fig. 4, the hub 17 is adapted to fit relatively loosely over the shaft 16 and rest on the armature 15. Thus it will be seen that as the motor 14 rotates, the shade 19 is rotated thereby due to the frictional engagement of the hub 17 with the armature 15, the shaft 16 serving to center the shade with the motor. The shade mounting just described is such that the shade 19 normally hangs in the vertical position shown in Fig. 1, but if forcibly tilted may rock up on the lower edge of the hub 17, the relatively loose fit of the hub and the shaft being such that the shaft is not liable to be bent by such rocking action.

The zoetrope portion of the device is formed in the shade 19 near its lower edge and comprises a series of evenly spaced and relatively narrow slits 20 parallel to the cylindrical axis and arranged in a band around the shade 19; and a series of animated cartoon pictures schematically designated by the letters A, B, C, etc. imprinted on the interior surface of the shade 19, each picture falling between two successive slits 20 in the area designated generally by the numeral 21 in Fig. 3.

An incandescent light bulb for the purpose of lighting the cartoon pictures and also for the purpose of providing general illumination is held in a conventional socket 27 fixed to the columnar support 11 by means of a collar 26. Current for the light bulb 28 and for the motor 14 is provided through a pair of leads 30 which are led through the columnar support member 11 which is made hollow for that purpose. Leads 29 from the motor are connected in parallel with leads for the light bulb 28 and the current supplied to both the motor 14 and the light bulb 28 is controlled by a switch (not shown) operated by a conventional pull chain 31.

It will be seen that a lamp constructed as just described serves to provide general illumination in the conventional manner, light rays from the bulb 28 being directed downwardly and upwardly by the shade 19. It will also be seen that the light bulb 28 serves the additional purpose of furnishing relatively intense illumination for the cartoon pictures.

When the shade rotates clockwise, that is, in the direction of the arrows shown in Fig. 2, the cartoon pictures pass from left to right across the back of the shade 19 and are scanned by the moving slits 20 which move from right to left across the front of the shade. Thus it will be seen that since the relative intensity of the light striking the cartoon pictures is very much greater than that striking the outside of the shade 19, the motion of the slits 20 will not be noticeable

against the relatively brilliant picture image. With this type of illumination, it is possible to view the animated picture from a point relatively distant from the lamp at which point the definition is greatly improved over that which is obtained when the eye is in close proximity to the slits 20.

One modification of my invention particularly adaptable to the device shown in Fig. 1 contemplates printing the animated cartoon pictures with luminous ink or paint. In this manner, luminous animated cartoons are produced which are visible after the light has been extinguished. It is desirable for this purpose to include a separate switch in order to extinguish the light without stopping the motor. A zoetrope operating on this principle is particularly effective in that the scanning slits are completely invisible, the only visible motion after extinguishing the light being the motion of the cartoon itself.

Both of the embodiments illustrated and described herein are intended as lamps for nurseries and children's playrooms. With the object of making these lamps more attractive to children, the motif expressed by the reclining figure 12 is repeated in the subject matter of the cartoon sequence. For example, the reclining figure 12 shown in Fig. 1 is decorated to represent the nursery rhyme character "Little Boy Blue" and to carry out this motif, the cartoon sequence may represent "the sheep in the meadow" or "the cow in the corn." Many other adaptations and modifications will of course occur to those skilled in the art.

While the apparatus described and illustrated herein is fully capable of attaining the objects and providing the advantages hereinbefore mentioned, it is merely illustrative of the broad scope of my invention as defined in the appended claims.

I claim:

1. In a display lamp, the combination of: a base; a vertical standard fixed to said base and projecting upwardly therefrom; a horizontal member projecting laterally from said standard adjacent the upper end thereof; motor means having a vertical upwardly extending axle thereon and mounted on said horizontal member; a tubular shade of substantially opaque material having spokes adjacent an upper edge thereof and being secured by said spokes to the axle of said motor means whereby to rotate about a vertical axis; a plurality of vertical scanning slits formed in said shade adjacent the lower edge thereof, said slits being arranged in a circumferential band adjacent the lower edge of said shade; a plurality of pictures imprinted on the interior surface of said shade, one between each adjacent pair of said slits, said pictures being adapted by progressive change in position of objects therein to produce the illusion of motion when viewed stroboscopically through said slits when said shade is rotated; and an electric light supported on said standard below said horizontal member, said light being positioned above the plane defined by said circumferential band of slits whereby to provide relatively intense illumination for said pictures as compared to the exterior surface of said shade, and whereby said pictures may be stroboscopically viewed without substantial distraction by the motion of said shade.

2. In a display lamp, the combination of: a base; a vertical standard fixed to said base and projecting upwardly therefrom; laterally extend-

ing support means fixed to said standard adjacent the upper end thereof; motor means having an upwardly extending axle and mounted on said support means; a tubular shade of substantially opaque material having means adjacent an upper edge thereof for mounting it on said motor axle whereby to rotate about a vertical axis; a plurality of vertical scanning slits formed in said shade adjacent the lower edge thereof, and arranged in a circumferential band adjacent said edge; a plurality of pictures on the interior surface of said shade, one between each adjacent pair of said slits, said pictures being adapted by progressive change in position of objects therein to produce the illusion of motion when viewed stroboscopically through said slits when said shade is rotated; and an electric light supported on said standard below said horizontal member, said light being positioned above the plane defined by said circumferential band of slits to thereby provide relatively intense illumination for said pictures as compared to the exterior surface of said shade, whereby said pictures may be stroboscopically viewed without distraction by the motion of said shade.

3. In a display lamp, the combination of: a base; a standard fixed to said base and projecting upwardly therefrom; a horizontal member projecting laterally from said standard adjacent the upper end thereof; motor means having a vertical upwardly extending axle thereon and mounted on said horizontal member; a tubular shade of substantially opaque material having spokes adjacent an upper edge thereof and being secured by said spokes to the axle of said motor means whereby to rotate about a vertical axis; a plurality of vertical scanning slits formed in said shade, said slits being arranged in a circumferential band adjacent an edge of said shade; a plurality of pictures on the interior surface of said shade, one between each adjacent pair of said slits, said pictures being adapted by progressive change in position of objects therein to produce the illusion of motion when viewed stroboscopically through said slits when said shade is rotated; and an electric light supported on said standard, said light being positioned within said shade intermediate its upper and lower edges and displaced vertically from the plane defined by said circumferential band of slits to thereby provide relatively intense illumination for said pictures as compared to the exterior surface of said shade, whereby said pictures may be stroboscopically viewed without substantial distraction by the motion of said shade.

4. In a display lamp, the combination of: a base; a standard projecting upwardly from said base; laterally extending support means fixed to said standard adjacent the upper end thereof; motor means having an upwardly extending axle and mounted on said support means; a tubular shade of substantially opaque material having means thereon for mounting it on said motor axle whereby to rotate about a vertical axis; a plurality of vertical scanning slits formed in said shade and arranged in a circumferential band adjacent an edge thereof; a plurality of pictures on the interior surface of said shade, one between each adjacent pair of said slits, said pictures being adapted by progressive change in

position of objects therein to produce the illusion of motion when viewed stroboscopically through said slits when said shade is rotated; and an electric light supported by said standard within said shade intermediate its upper and lower edges and displaced vertically from the plane defined by said circumferential band of slits to thereby provide relatively intense illumination for said pictures as compared to the exterior surface of said shade, whereby said pictures may be stroboscopically viewed without substantial distraction by the motion of said shade.

5. In a display lamp, the combination of: a base; a standard projecting upwardly from said base; support means on said standard adjacent the upper end thereof; motor means mounted by said support means; a tubular shade of relatively opaque material; means for rotatably mounting said shade about a vertical axis and operatively connecting the same to said motor means for rotation thereby; a plurality of vertical scanning slits formed in said shade, said slits being arranged in a circumferential band adjacent an edge of said shade; a plurality of pictures on the interior surface of said shade, one between each adjacent pair of said slits, said pictures being adapted by progressive change in position of objects therein to produce an illusion of motion when viewed stroboscopically through said slits when said shade is rotated; and an electric light positioned within said shade intermediate its upper and lower edges and displaced vertically from the plane defined by said circumferential band of slits to thereby provide relatively intense illumination for said pictures as compared to the exterior surface of said shade, whereby said pictures may be stroboscopically viewed without substantial distraction by the motion of said shade.
